United States Patent Office

Des. 184,847
Patented Apr. 14, 1959

184,847

AUTOMOBILE TOP CARRIER

Raymond R. Barnett, Macomb County, and
Howard G. Roth, Oakland County, Mich.

Application April 9, 1956, Serial No. 40,978

Term of patent 14 years

(Cl. D14—27)

Fig. 1 is a side elevational view of an automobile top carrier embodying our new design;

Fig. 2 is a perspective view of the automobile top carrier as seen from one side thereof; and

Fig. 3 is a perspective view of the automobile top carrier as seen from the other side thereof.

The portions shown in broken lines are for the purposes of illustration only.

We claim:

The ornamental design for an automobile top carrier, as shown and described.
